UNITED STATES PATENT OFFICE.

GEORGE E. HAIGHT, OF HARTFORD, CONNECTICUT, ASSIGNOR OF ONE-HALF
TO WILLIAM E. WINSOR, OF NEW YORK, N. Y.

DEVICE FOR CONTROLLING TORPEDO-BOATS.

SPECIFICATION forming part of Letters Patent No. 257,694, dated May 9, 1882.

Application filed September 7, 1881. (No model.)

To all whom it may concern:

Be it known that I, GEORGE E. HAIGHT, a citizen of the United States, residing at Hartford, in the county of Hartford and State of Connecticut, have invented certain new and useful Improvements in Devices for Controlling Torpedo-Boats; and I do hereby declare the following to be a full, clear, and exact description of the invention, such as will enable others skilled in the art to which it appertains to make and use the same, reference being had to the accompanying drawing, and to the letters or figures of reference marked thereon, which forms a part of this specification.

This invention relates to valves for controlling the operative parts of self-propelled torpedo-boats and methods of actuating the same.

It has for its object the construction of such valves and manner of operating them, whereby the liability of their freezing, due to the rapid expansion of the gas, either in liquid or gaseous form, (and which is employed as the motive force,) will be entirely obviated.

My invention consists of a storing-reservoir for liquefied gas under pressure, having a condensing-pipe leading from both the upper and the lower end thereof, whereby the liquid and the gas contained in said reservoir may be conducted therefrom separately and utilized jointly in a throttle-valve apparatus of a gas-engine.

My invention also consists in a reservoir of the above description in combination with a throttle-valve apparatus of a gas-engine in such manner that the pressure of the gas in the reservoir may be exerted to open and close a valve controlling the supply of liquid in the same.

My invention further consists in a device comprising essentially a valve for controlling the liquid-supply, a cylinder having a valve (operated by electro-magnetic energy or other suitable power) with its ports in communication with the gas in the reservoir and with the cylinder, and connection with the piston-head of said cylinder and the valve for controlling the liquid-supply, whereby the pressure of gas within the reservoir may be used to shift the liquid-controlling valve.

The drawing represents a longitudinal section of a portion of a torpedo-boat, showing a

portion of the reservoir, and my improved construction and arrangement of the throttle-valve apparatus, and also the expansion-pipes.

A represents the reservoir or flask for storing, under pressure, carbonic-acid, nitrous-oxide, or similar liquefied gas.

B is a cock in the siphon-pipe b, which leads from the liquid in the reservoir A and connects with the coiled pipes H.

D is a valve in the siphon b, which, when open, permits the liquid from the reservoir to pass into the expansion-coils H.

E is a cylinder, by means of which the valve D is operated.

F is a slide-valve, by means of which gas from the upper portion of the reservoir may be admitted to the cylinder E through pipe c. This slide-valve is opened or closed by means of an electro-magnet, as at G, in the usual manner in the Lay torpedo-boats.

The cock B is normally open. We will suppose the slide-valve F to be closed. The pressure of gas in the reservoir drives the liquid up through pipe b as far as the valve D, but as there is no great expansion the liquid is not liable to freeze. To start the boat or engine, the valve F is then opened, which permits the gas from above the liquid in the reservoir to pass through pipe c into cylinder E, and by means of piston e and piston-rod e' the valve D is forced open. The liquid in the reservoir will now be forced through pipe b into pipe H, which may be coiled in any suitable way, and is in contact with the sea-water either by the admission of the latter into a compartment of the boat or by coiling the pipe outside the boat, or other appropriate means may be provided for imparting heat to the expansion-pipes. Expansion of the gas takes place in this pipe H, the heat necessary to prevent freezing being supplied by the sea-water or other means, and the gas passes on to the engine, which I have not thought it necessary to show in the drawing.

It will be observed that the gas drawn from the reservoir at any one time is only the small quantity necessary to move the piston in cylinder E to one end or the other of said cylinder. As the valve F is shifted by the magnet it permits this small quantity to escape through an

exhaust-port, e^2 . The gas to drive the engine expands from the liquid in the coiled pipe H , away from the main body of the liquid in the reservoir. Consequently there is little tendency 5 of the latter to freeze. This construction and arrangement of the valvular apparatus I have found a practical one. The magnet G has but to move slide-valve F , which is not likely to freeze in place. The whole gas-pressure in the 10 reservoir can be thrown upon piston e' , so as to open valve D , which leads to the engine, thus giving great power for such operation.

It will be obvious that the application of my 15 invention may not be limited to that of a torpedo-boat, and I wish it so understood.

The valve devices are applicable to almost all forms of gas-engines where there is a liability of the liquid or gas, through rapid expansion, to congeal in the engine-supply pipe.

20 Having described my invention, what I claim is—

1. In a valve apparatus for torpedo-boats, a reservoir containing liquefied gas under pressure, having a pipe leading from the liquid and 25 a pipe leading from the gas therein, substantially as described, and for the purpose set forth.

2. A reservoir containing liquefied gas under pressure, having a pipe leading from the liquid and a pipe leading from the gas therein, in 30 combination with a valve apparatus, substantially as described, whereby the pressure from the gas contained in the reservoir is applied to shift the liquid-controlling valve.

3. In combination with a valve apparatus 35 for torpedo-boats, the reservoir A , having the pipe c in communication with the top and pipe

b in communication with the bottom thereof, substantially as and for the purpose described.

4. A reservoir containing liquefied gas under pressure, having a pipe leading from the liquid therein to and in combination with an expansion chamber or pipe, the passage thereto being controlled by a valve, and said reservoir having another pipe leading from the gas therein to valve apparatus, substantially as 45 described, whereby the pressure of gas contained in the reservoir is used to shift the said liquid-controlling valve, for the purposes described.

5. In a valve apparatus for torpedo-boats, 50 the combination of cylinder E , slide-valve F , magnet G , piston e , piston-rod e' , and valve D , substantially as described.

6. The combination, with the gas-reservoir, 55 of a pipe, c , leading from the gas in the reservoir to cylinder E , and pipe b , leading from the liquid in the reservoir to the expansion-pipes, but closed or opened by valve D , which is operated by the piston in cylinder E , substantially as described.

7. The combination of reservoir A , gas-pipe c , and liquid-pipe b , valve F , operated by magnet-cylinder E , valve D , operated as described, and expansion-pipes leading to the engine, substantially as shown and described. 60 65

In testimony whereof I affix my signature in presence of two witnesses.

GEORGE E. HAIGHT.
